Z. B. BELLows.
CHAIR SEAT.

No. 23,225.

Patented Mar. 15, 1859.

UNITED STATES PATENT OFFICE.

ZEBULON B. BELLOWES, OF CORTLANDVILLE, NEW YORK.

CHAIR-BOTTOM.

Specification of Letters Patent No. 23,225, dated March 15, 1859.

To all whom it may concern:

Be it known that I, ZEBULON B. BELLOWES, of Cortlandville, in the county of Cortland, in the State of New York, have invented an
5 Improved Mode of Seating Chairs; and I do hereby declare that the following is a full and exact description of the said invention.

The nature of my invention consists in providing bent, stamped or pressed seats for
10 chairs, of any or all kinds or qualities, made of boards or plank, so that the form or shape of the seat will fit and conform to the shape
of the person who shall occupy the chair.

To enable others to make and use my invention, I will describe the construction and
15 operation of my chair seat.

First I take the boards and saw them to the required length for a single seat. I then boil or steam them, then put them into a mold and apply the power of a press sufficient to form them in a concave form and of the desired shape. The mold may be constructed of wood or iron.

What I claim as my invention and desire to secure by Letters Patent is—

25 The application to chairs of a bent, stamped or pressed board for a seat.

ZEBULON B. BELLOWES.
